UNITED STATES PATENT OFFICE.

GERALD H. MURPHY, OF FLUSHING, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed December 5, 1924. Serial No. 754,085.

This invention relates to stencil-card holding and typing devices for typewriting machines.

One of its features is the provision of improved means for automatically controlling the ribbon mechanism, so that it may be thrown in front of the types at certain times, but withdrawn while the type is striking the stencil-blank.

10 This device is particularly adapted for use in connection with stencil-cards for addressing machines which comprise a comparatively heavy paper or cardboard frame, having an opening, across which is stretched a stencil-sheet. It is generally required to write the name or other identification mark at the top edge of the card, on the paper frame, and then the full name and address are typed on the stencil-sheet.

20 One of the features of this invention is the provision of means for handling said card with the minimum effort, and consequently means is provided whereby the card may be easily inserted in a frame, whereon it is supported by spring-fingers. The frame supporting the card is geared to the platen by means of a gear-and-rack arrangement in such a way that when the platen is turned forwardly, the frame and the card thereon are lowered, and, when the platen is rotated rearwardly, the lines are spaced in the card similarly as if the card was fed around the platen in the ordinary way. Having inserted the card in the frame, the platen is 30 rotated by means of a lever or crank at one end of the platen-shaft and the frame is lowered to a stop which locates the position of a line of typing near the leading edge of the card. At this time it is required to type a line by means of the ribbon, and, for this purpose, mechanism is provided co-operating with the lower end of the frame for automatically elevating the ribbon to effectively interpose the type. Thus the first 40 line, near the top edge, is typed on the paper frame in a manner as it would be done in a regular typewriting machine.

In order to type a second line, which, in this case, would be the first line on the stencil-blank, the lever at the end of the platen is swung backwardly to a stop which determines the position of the first line. As the lever is swung and the frame is moved upwardly the ribbon-elevating mechanism is released and the ribbon is allowed to

sink down to a position out of the range of the type, so that a line of type may be cut into the stencil-blank. Successive lines of type may be cut into the stencil by line-spacing the platen in the regular way, and, for this purpose, mechanism has been provided whereby the stop controlling the position of the first line in the stencil-blank is released when the line-space lever is actuated.

60 Said mechanism comprises a pawl which normally interposes a tooth in a disk fast on the platen-shaft, and, by means of a link operatively connected to the line-space lever, the pawl is withdrawn from in front of the tooth in said disk at every actuation of the 65 line-space lever.

Other features and advantages will hereinafter appear.

In the accompanying drawings,

70 Figure 1 is a cross-sectional view, in elevation, through the line 1—1 of Figure 4, showing a Remington typewriting machine having the invention applied thereto.

75 Figure 2 is a fragmentary side elevation, partly in section, illustrating the method of locking the platen-frame in lower-case position.

80 Figure 3 is a fragmentary side elevation, showing a disk on the platen-shaft co-operating with a tooth cut into the disk.

85 Figure 4 is a plan view, showing the carriage of a Remington typewriting machine having the invention applied thereto.

90 Figure 5 is a rear view, in elevation, of the stencil-frame and is shown partly in cross-section through the line 5—5 of Figure 1.

95 Figure 6 is a plan view of the pawl-and-disk arrangement, illustrating the pawl as it is connected with the line-space lever in a released position.

Figure 7 is a plan view of the work-sheet or card, showing lines of typing thereon.

100 Figure 8 is a cross-sectional view, in elevation, through the line 8—8 of Figure 4, showing the card in a position for cutting lines of typing on the stencil-blank.

105 Figure 9 is a fragmentary side view, in elevation, showing the line-spacing mechanism and the pawl-releasing mechanism attached thereto.

110 Figure 10 is a diagrammatic view, in side elevation, showing the relative position of the ribbon-mechanism when lowered to clear the type when typing upon the stencil-blank.

Referring more particularly to Figure 1

in the drawings, a Remington typewriting machine is illustrated into which there is built a stencil-device which forms the subject of this invention. Numeral 10 indicates the typewriter-frame, 11 is the carriage, 12 are the keys which are operatively connected to type-bars 13 by means of the links 14 and 15 actuating on a bell-crank 16. The type-bars 13 are pivoted at 17 and are swung thereon for striking the types 18 against a platen 19 which is revolubly mounted on the carriage 11.

A card 20 is inserted in a frame 21, between finger-springs 22, which hold the card 15 in a position as shown in Figure 5. The frame 21 is operatively engaged with the platen by means of a gear-and-rack arrangement comprising the racks 23 and the gears 24. Said gears 24 are fast on the platen 19 20 and are operatively connected to the frame 21 by means of the racks 23 which operate the latter when the platen is rotated. The frame 21 is slidably mounted on a fixed frame which comprises supporting members 25 25 and cover-plates 26 fastened to the members 25 by means of screws 27.

The frame 21 and the card 20 are then lowered to a position, against a stop 29, so that a line of typing 30, near the leading 30 edge of the card, may be typed thereon. In order to lower the frame 21, the platen is swung forwardly by means of a lever 31 fast on the platen-shaft 32.

It is desired to type the first line of type 35 30 on the frame 33 of the card 20 by interposing a ribbon 34 between the card and the types 18. To this end, there is provided mechanism whereby the ribbon 34 may be elevated to its effective position as shown 40 in Figure 1. Normally the ribbon 34 is held in its ineffective position as shown in Figure 8, clearing the type. When the stencil-frame 21 is lowered, its lowermost edge 35 strikes a forwardly-extending arm 36 of a bell-crank 37 which is pivoted at 38 on a downwardly-extending bracket 39, fast to the typewriter-frame 10. A downwardly-extending arm 40 of said bell-crank 37 engages an upwardly-extending arm 41 of another bell-crank 42 pivoted on a screw 43 fast to the bracket 39. Said bell-crank 42 is provided with a forwardly-extending arm 44, the end of which is operatively connected with a ribbon-lifting frame 45, the uppermost end of which carries the ribbon 34.

It will be apparent that when the frame 21 is lowered and its lowermost end 35 strikes the arm 36 of the bell-crank 37, the ribbon 34 will be elevated to a position in front of the type, so that when the keys 12 are struck and the type-bars swing, the types 18 will make impressions on the card. A spring 46 is provided for the purpose of rendering ineffective the ribbon 34 when the

pressure on the bell-crank 37 is released. Said spring 46 is fastened to the bell-crank 42 by means of a pin 47 and to the bracket 39 by means of a pin 48, and is normally under tension tending to lift the arm 36 of the bell-crank 37 and to lower the arm 44 of the bell-crank 42 upon which the ribbon-lifting frame is mounted. Said lifting frame 45 is slidably mounted on a guiding member 96 fastened to the type-bar-segment 10^a by 75 means of screws 97. It will be noted that the lifting frame 45 is made of flat material and at the uppermost end a wire 98 is provided for supporting and lifting the ribbon 34. 80

Since one of the purposes of this invention is to facilitate the writing on a stencil having edge-enclosing frames where it is desired to ink type upon the frame, near the leading edge, and to cut through the stencil-blank with the bare type, it will be necessary to withdraw the ribbon from in front of the type in order to cut the first line of typing 49 on the stencil-blank. This is done automatically by the spring 46 when the frame 21 is raised and the bell-crank 37 is therefore released. 85

In order to raise the frame 21 so as to bring the stencil-card in a position for cutting the first line of typing thereon, the lever 31 is swung rearwardly up to a position where a pawl 50, mounted on the carriage of the typewriter, interposes a tooth 51 cut in a disk 52 which is fast on the platen-shaft 32. This position is designed 100 to correspond with the position of the first line on the stencil-blank. The pawl 50 is pivoted on a screw 53 fast on the typewriter-carriage 11, and is held bearing against the disk 52 by means of a spring 54. 105

When it is desired to cut more lines of typing on the stencil-blank, the distance between them should be uniform, and, to this end, means are provided whereby the line-spacing lever 55 may be used and the card 110 raised one space at a time for successive lines of typing. The lever 55 is swung on a bearing-and-shaft arrangement 56, and has at the rearmost end a crank 57 fast to the lever by means of a screw 58. Said crank 57 is 115 operatively connected to a bell-crank 59 by means of a link 60, in such a manner that when the lever 55 is swung, the link 60 is moved downwardly, and, by rocking the bell-crank 59 on a pivot 61, a link 62, operatively connected to the bell-crank 59 by means of a pin 63, is forced rearwardly to 120 thus throw a pawl 64 into engagement with a ratchet 65 fast on the shaft 32. The pawl 64 is pivoted at 66 upon a lever 67 which is 125 fulcrumed on the platen-shaft 32, so that when the link 62 is moved rearwardly, due to its being connected to the pawl 64, it will first throw the pawl into engagement with the ratchet and then will feed the same in 130

line-space direction up to the point where a rearwardly-extending heel 69 strikes a roller 70, which is resiliently mounted on a spring 71 and acts as a retainer for the ratchet 65.

- 5 In order that the platen may be fed, it is necessary first to withdraw the pawl 50 from in front of the tooth 51 in the disk 52. To this end, there is provided mechanism whereby the first portion of the travel of the lever 10 55 is utilized to withdraw said pawl and which may comprise a rearwardly-extending link 72 operatively connecting the pawl at 73 and the bell-crank 59 at 74, so that as the bell-crank is swung forwardly the link 72 15 will push on and rock the pawl 50 away from the disk 52, thereby clearing the tooth 51. There is provided a plate 75 having the upper end 76 bent for taking the upward thrust of the pawl 50 when struck by the tooth 51 on the disk 52, said plate being fastened to the carriage-frame by means of a screw 77. It will be noted that the lever 55 is returned to normal position by the spring 78.
- 25 The Remington typewriting machine is normally operated in lower-case position and is usually provided with mechanism for elevating the platen to upper-case. Said mechanism includes a platen-frame 79 supported by links 80 which are pivoted at 81 on the carriage and serve to support the frame 79 and to move the same in a straight up and down line. Since this mechanism is not necessary in this type of a device in 30 which it is desired to type all characters in lower case, there are provided screws 82 to lock the platen in lower-case position, and thus prevent its accidental shifting to upper case. The stencil-device is mounted between 35 side frames 25, secured on a shaft 84 by means of screws 83, and is spaced between two collars 85, which position the same. A tie rod 86 unites the members 25 so as to keep the several associated parts together when the device is withdrawn from the machine. Said shaft 86 is fastened to the members 25 by means of fasteners which are shown in the drawings in the form of screws 40 87 and nuts 87a.
- 45 It is customary to provide a backing for the types in the form of a celluloid covering 88 around the platen, and, due to the fact that it is exposed to the type-blows, it is desired to mount it on the platen in a manner 50 which will render it easily removable. To this end, there are provided two clamps 89 and 90 fastened to the platen by means of screws respectively numbered 91 and 92. Said clamps are made of resilient material 55 and are so designed that the heads of the screws holding them are sunk into the platen in order that the card 20 may not interfere with the head of the screws when the platen is rotated to operate the card-frame.
- 60 A special scale 93 in the front of the ma-

chine has been provided, substituting the regular scale, and the stops 94, normally adjustable, have been fixed by means of screws 95 in order that the travel of the carriage may be limited within the range of the card. 50

It will be noted that the platen 19 is made comparatively smaller than the regular platen, as in many cases it may be required to use the machine with a double-shift case, and it has been found in practice that a 75 platen of small diameter reduces considerably the possibility of double printing.

Variations may be resorted to within the scope of the invention, and portions of the improvements may be used without others. 80

Having thus described my invention, I claim:

1. The combination, in a typewriting machine, of a revoluble platen, a frame, arranged in front of the platen, to reciprocate 85 a stencil-card tangentially to the platen, a ribbon normally inoperative below the printing line, and mechanism controlled by said frame to be operated by the movement thereof to position for typing a line on the top 90 of the frame, for elevating the ribbon to the printing line.

2. The combination, in a typewriting machine, of a revoluble platen, a stencil-card-carrying frame arranged to reciprocate tangentially to said platen, a stop-device co-operating with the bottom edge of said frame to position the card for a first line of typing upon the upper edge thereof, automatic means for positioning the card for a second 95 line of typing thereon, and means for line-spacing the card, said last-mentioned means being also effective to render ineffective said automatic means. 100

3. The combination, in a typewriting machine, of a revoluble platen, a card-carrying frame operatively connected to said platen in a manner to reciprocate tangentially in front thereof, means for positioning the card for a first line of typing upon the top edge 105 thereof, means including a stop-device co-operating with the platen for positioning the card for a second line of typing thereon, and a line-spacing mechanism effective to render ineffective the stop-device and to line-space the card. 110

4. The combination, in a typewriting machine, of a revoluble platen, a line-spacing mechanism therefor, a work-sheet-carrying frame slidable tangentially to said platen, means for rotating said platen, a stop co-operating with said carrying frame for positioning a work-sheet for a first line of typing, a stop co-operating with the platen for positioning the work-sheet for a second 120 line of typing, and means controlled by said line-spacing mechanism for rendering ineffective the stop which co-operates with said platen. 125

5. In a typewriting machine, the combina- 130

tion with a revolute platen, of a card-holding frame in front thereof to receive a card to be stenciled and written upon, a normally ineffective ribbon below the printing line, and means for automatically elevating the ribbon in front of the types when the card is completely lowered to type a line at the upper edge thereof.

6. In a typewriting machine, the combination with a revolute platen, and a normally ineffective ribbon mechanism, of a movable card-holding frame in front of the platen to receive a card to be stenciled and written upon, the ribbon being inoperative below the printing line when the card is stenciled upon, and means controlled by the movement of said frame for automatically elevating said ribbon mechanism when writing upon the card.

7. In a typewriting machine, the combination with a revolute platen and a normally ineffective ribbon, of a card-holding frame in front of said platen to receive a card upon which a line of typing is to be written near its leading edge and a plurality of lines are to be stenciled upon a stencil-sheet in the center of said card, stop devices for positioning said card for the different lines of typing and stenciling thereon, and means controlled by said card-holding frame for elevating the ribbon when the card is lowered to receive typing upon its leading edge.

8. The combination with a typewriting machine including a revolute platen and a normally ineffective ribbon, of a card-carrying member operatively connected to said platen, and means controlled by said card-carrying member for rendering effective said ribbon, said means including a pair of bell-cranks operatively connecting said card-carrying frame to said ribbon in a manner to elevate the latter in front of the types when the frame is lowered to engage with one of the bell-cranks.

9. The combination with a typewriting machine including a revolute platen and a line-spacing mechanism therefor, of a card-carrying frame operatively connected to said platen in a manner to reciprocate tangentially thereto, and ribbon control means actuated by the downward movement of the card-carrying frame, said means being effective to control the elevating movement of the ribbon.

10. The combination with a typewriting

machine including a revolute platen, of a card-carrying frame reciprocating tangentially to said platen, means for positioning a stencil-card for a first line of typing near the leading edge thereof, and means for rotating the platen against a stop and for positioning the card for a second line of typing thereon, said last-mentioned means including a disk fast on the platen shaft, a pawl co-operating with a notch in said disk, and resilient means for holding the pawl to bear against said disk and in the path of said notch.

11. The combination with a typewriting machine including a revolute platen and a line-spacing mechanism therefor, of a card-carrying frame operatively connected to said platen and reciprocating tangentially thereto, means for positioning a stencil-card for a first line of typing, means for positioning the card for a second line of typing thereon, said last-mentioned means including a disk fast on the platen shaft and having a tooth co-operating with a pawl resiliently held bearing against said disk, so as to interpose said tooth and to stop the rotation of the platen, and means controlled by the line-spacing mechanism, whereby the pawl will be withdrawn from in front of said tooth upon operation of said line-spacing mechanism.

12. The combination, in a typewriting machine, of a revolute platen having means for engaging and reciprocating a card-carrying frame in front thereof, means for guiding said frame, resilient means for holding a stencil-card in said frame, a ribbon normally ineffective below the printing line, and means for elevating the ribbon in front of the types upon lowering the card-carrying frame to a position to receive a line of typing upon the top margin of the card.

13. The combination, in a typewriting machine, of a revolute platen, a card-carrying frame arranged to reciprocate tangentially in front of the platen, a normally ineffective ribbon, a supporting member therefor arranged to reciprocate up and down to present to or withdraw the ribbon from the printing point, and means for operatively connecting the card-carrying frame to the ribbon-supporting member in a manner to elevate the latter during the last line-spacing movement of the former.

GERALD H. MURPHY.
